SLIDING SUPPORT MECHANISM

David E. Hartman, Toronto, Ontario, Canada

Application December 16, 1950, Serial No. 201,097

6 Claims. (Cl. 311—46)

1

This invention relates to a sliding support mechanism for a removable leaf type table top adapted to slidably mount two main table top halves and to retractably support a leaf board.

The sliding support mechanism of the invention is of that type which is mounted in such manner that two of such mechanisms are disposed in parallel spaced apart relation and serve to slidably fasten the components of the table top to the frame of the table.

The objects of the invention will be appreciated by a study of the following specification taken in conjunction with the accompanying drawings.

In the drawings:

Figure 1 is an elevation of a sliding support mechanism according to the invention illustrating the disposition of its components when the leaf board of the table top is retracted and out of view.

Figure 2 is a further elevation of the device of Figure 1 but illustrating the positions of the components thereof when the leaf board is raised thereby to effect an expanded length for the table top.

Figure 3 is an end view of one of the retractable leaf levers of the mechanism of Figures 1 and 2 illustrating its general construction.

Referring to the drawings, the sliding support mechanism herein comprises the mounting plate 10 which is adapted to be fastened to the frame of a table such as a horizontal member extending between the upper ends of the legs on one side. The mounting plate may be fastened to such horizontal member in any suitable way. I provide two slidable members 11 and 12 riding on vertically spaced apart slots such as the slots 13 in the mounting plate 10 and the slot 14 in the member 11. These slots are engaged by guide means such as the pin 15 extending from mounting plate 10 and the pin 16 extending from the member 11 to move in the slot 13 of the mounting plate 10. The length of the slots 13 and 14 determine the limits of slidable movement of slidable member 11, which latter carries a main table top half 17 on its upper flange 18, the same being mounted in such manner that another main table top half 19 is adapted to meet the former at a medial line 20 when the slidable members 11 and 12 are disposed in their most inward position as determined by their mounting slots 13 and 14 and pins 15 and 16. In this position of the components, a retractable leaf 21 supported by bracket member 22 is disposed below the plane of the main table top

2

halves 17 and 19 in the manner indicated in Figure 1. The bracket 22 has upwardly inclined and converging slots 23 and 24 which, in their lower outer terminus, define enlarged openings 25 and 26 constituting supporting seats or shoulders designed to be engaged by the sliding pins 27 and 28 extending from retractable levers 29 and 30.

The retractable levers 29 and 30 are pivotally mounted on suitable screws or rivets 31 and 32 extending from the mounting plate 10. In the position of the components illustrated in Figure 1 it will be observed that the sliding members 11 and 12 are operatively related in their sliding movement. Thus, a flexible metal strap 33 extends from rigid connection as at 34 to the slidable member 11 about the pulley wheel 35 rotatably mounted on a shaft 36 extending from the mounting plate 10 and passes to an end fastening member 37 having an eyelet 38 therein adapted to fasten about a projection 39 from a flange 40 of the slidable member 12. Similarly, a flexible metal strap member 41 extends from fixed connection as at 42 to the member 12 about the pulley 43 rotatably mounted on the shaft 44 fixed to the mounting plate 10 to a similar end fastening member 45 having an eyelet 46 through which a projection 47 extends from a lower flange 48 of the slidable member 11. In this way, movement of either of the slidable members 11 or 12 relative to the mounting plate in the direction of the slots 13 and 14 will cause corresponding but opposite movement of the other slidable member.

35 I provide enlargements in the form of lugs 49 and 50 on each of the straps 33 and 41 and which are adapted to engage actuating flanges 51 and 52 of the retractable levers 29 and 30 when the slidable members 11 and 12 are moved toward their outermost position as illustrated in Figure 2. To facilitate this function, I slot each of the actuating flanges to accommodate their respective straps and thus, as illustrated in Figure 3, the lever 29 carrying its actuating flange 51 has a suitable slot 53 in the latter adapted for free passage of the strap 41.

As the retractable levers 29 and 30 are swung outwardly by the enlargements or lugs 49 and 50, the sliding pins 27 and 28 move to a position to engage the seats 25 and 26 of the retractable bracket 22 and at the same time cause said bracket to rise to a position whereat the retractable leaf 21 thereof arrives at common planar relationship with the main table top halves 17 and 19. 55 As will be observed in Figure 2, the retractable

leaf member 21 is shown in slightly spaced relationship to the main table top halves corresponding to the outward limit of slidable travel of the slidable members 11 and 12. Accordingly, as these latter members are moved into mating relationship with the retractable leaf, the lugs 49 and 50 will be moved toward one another away from engagement with the flanges of the retractable levers. Nevertheless the enlargements 25 and 26 sufficiently support the retractable leaf so that no difficulty has been found in practice with this simple arrangement.

When moving the slidable members 11 and 12 again to cause the retractable leaf to retract, they are merely moved to the position illustrated in Figure 2 and then with a very slight pressure exerted by the operator and a slight movement of the retracted leaf, the bracket 22 is quickly unseated from the pins 27 and 28 and falls under its own weight substantially to the position illustrated in Figure 1 whereat the slidable members 11 and 12 may be moved inwardly to join at the medial line 20 of the main table top halves 17 and 19.

The slidable members 11 and 12 may be locked at positions illustrated in Figure 1 and in position of closure of their main table top halves 17 and 19 with the retractable leaf 21. This may be accomplished by providing a locking member 54 mounted by means of a rivet 55 to the mounting plate 10 and in such manner that the locking member is joined stiffly thereto and must be positively moved by an operator engaging the actuating flange 56 thereof to cause its locking finger 57 to engage within the locking hole 58 of flange 48. In operation, when it is desired to separate the sliding members 11 and 12 as illustrated in Figure 1, the locking member is rotated clockwise to disengage its finger 57 from the locking hole 58 after which the sliding members may be outwardly moved as previously discussed to cause the retractable leaf to rise to the position illustrated in Figure 2. When the sliding members are moved inwardly for closure with the exposed retractable leaf 21 the secondary locking opening 59 will come into registry with the finger 57 of the locking member 54 at which point of operation the operator may press the actuating flange 56 to cause the member to rotate counterclockwise and affect engagement of its finger 57 with the locking opening 59. It will be apparent that for a pair of sliding support mechanisms as disclosed herein only one locking member 54 need be provided. Moreover, the operator may stand at one end of the table and lock and unlock the mechanism as may be required as well as effect exposure or retraction of the retractable leaf 21 as may be desired.

It is intended that the present disclosure should not be construed in any limiting sense other than that indicated by the scope of the following claims.

What I claim as my invention is:

1. In a sliding support mechanism for a retractable leaf type table top adapted to mount two main table top halves, the combination of: a mounting plate, a pair of opposed support members slidably mounted on said mounting plate and movable in a direction toward and away from a common theoretical medial line therebetween, means on each of said slidable support members adapted to mount a main table top half whereby two table top halves are disposed in coplanar relationship, a retractable bracket member and means thereon for supporting a retract-

able leaf between said slidable support members, retractable levers pivotally mounted on said mounting plate between said slidable members and deflectable from a substantially vertical 5 parallel spaced apart position toward the medial line, means near the free ends of said levers for supporting said bracket and for moving it from a retracted position wherein the leaf member thereon is disposed below the plane of said main 10 table top halves to an outward position coinciding with the plane of said table top halves when said levers are disposed in substantially parallel spaced apart manner, and means operatively relating sliding motion of each sliding member with 15 the other and including means for engaging said retractable levers to cause swinging movement of the latter to their substantially vertical positions when said slidable members are moved outwardly with respect to one another.

2. A sliding support mechanism as claimed in claim 1 in which the means operatively relating each sliding member to the other, comprises: a flexible strap member having one end fastened to one slidable member and the other end fastened 25 to the other slidable member, a pulley wheel on said mounting plate about which said strap member passes, said pulley wheel being located at all times at a position outside positions in between the terminal ends of said straps whereby the 30 movement of one slidable member toward the medial line causes corresponding movement of the other slidable member.

3. A slidable support mechanism for a removable leaf table top as claimed in claim 1 in which the means operatively relating each sliding member to the other, comprises: a pair of flexible but substantially non-yieldable strap means each of which has one end fastened to one slidable member and the other end fastened to the other 35 slidable member, a pulley wheel mounted on the mounting plate for each of said strap means and located outside points between the limits of movement of the ends of the strap means.

4. A slidable support mechanism for a removable leaf type table top as claimed in claim 1 in which the means operatively relating each sliding member to the other, comprises: a pair of flexible but substantially non-yieldable strap means each of which has one end fastened to one 45 slidable member and the other end fastened to the other slidable member, a pulley wheel mounted on the mounting plate for each of said strap means and located outside points between the limits of movement of the ends of the strap means, and an enlargement on each of said strap means 50 designed to engage one of said retractable levers to cause the latter to swing to a position to move said leaf supporting bracket to an outward position co-planar with the main table top halves and when said slidable members are moved 55 in a direction away from the medial line.

5. A slidable support mechanism for a removable leaf type table top as claimed in claim 1 in which the means operatively relating each sliding member to the other, comprises: a pair of flexible but substantially non-yieldable strap means each of which has one end fastened to one slidable member and the other end fastened to the other 60 slidable member, a pulley wheel mounted on the mounting plate for each of said strap means and located outside points between the limits of movement of the ends of the strap means, an enlargement on each of said strap means 65 designed to engage one of said retractable levers to cause the latter to swing to a position to move said leaf 70 supporting bracket to an outward position co-planar with the main table top halves and when said slidable members are moved in a direction away from the medial line.

supporting bracket to an outward position co-planar with the main table top halves and when said slidable members are moved in a direction away from the medial line, and means on each lever for accommodating one of said strap means designed to be engaged by the enlargement thereon.

6. A slidable support mechanism for a removable leaf type table top as claimed in claim 1, and a locking member having a locking finger movably mounted on said mounting plate and adjacent a slidable support member thereof, and means on said adjacent slidable support member designed to be engaged by the finger of said locking member when said slidable support member is in positions wherein the main table top half thereon substantially meets the medial line and

is substantially in abutment with said retractable leaf.
